(57) **CLAIM**

The ornamental design for an imaging machine, as shown and described.

DESCRIPTION

FIG. 1 is a front perspective view of an imaging machine showing our new design with the lid closed.

FIG. 2 is a rear perspective view thereof.

FIG. 3 is a front view thereof.

FIG. 4 is a left side view thereof.

FIG. 5 is a right side view thereof.

FIG. 6 is a rear view thereof.

FIG. 7 is a top view thereof.

FIG. 8 is an alternate front perspective view of the imaging machine with the lid open.

FIG. 9 is a left side view thereof.

FIG. 10 is a right side view thereof; and,

FIG. 11 is a top view thereof.

The bottom views form no part of the design and are omitted. Alternate front and rear views of the imaging machine with the lid open have been omitted since they are identical to FIGS. 3 and 6, respectively.

The broken line showing is for the purpose of illustrating portions of the imaging machine and forms no part of the claimed design.
